ENDLESS BELT WHEEL CLEAT

Jack V. Knowles, East Lansing, Mich., assignor to Globe Trotter Corporation, East Lansing, Mich., a corporation of Michigan

Filed May 27, 1966, Ser. No. 2,458

Term of patent 14 years

(Cl. D43—1)

FIGURE 1 is a perspective view of endless belt wheel cleat, showing my new design;

FIGURE 2 is a side elevational view thereof;

FIGURE 3 is an end elevational view thereof;

FIGURE 4 is a cross sectional view thereof taken on line II-II of FIGURE 2;

FIGURE 5 is a cross sectional view thereof taken on line III-III of FIGURE 3.

The broken lines showing additional cleats, and portions of a wheel and belt are for illustrative purposes only.

I claim:

The ornamental design for an endless belt wheel cleat, as shown and described.
